(57) **CLAIM**

The ornamental design for a log splitter, as shown and described.

DESCRIPTION

FIG. 1 is a top front perspective view of a log splitter showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom rear perspective view thereof.

The dashed broken lines in the drawings illustrate portions of the log splitter that form no part of the claimed design.

1 Claim, 8 Drawing Sheets
